UNITED STATES PATENT OFFICE.

FRANK A. NIEBERDING, OF CLEVELAND, OHIO.

DESIGN FOR A HEATER.

Application filed February 3, 1922. Serial No. 522. Term of patent 7 years.

To all whom it may concern:

Be it known that I, FRANK A. NIEBERDING, a citizen of the United States, residing at Cleveland, in the county of Cuyahoga and State of Ohio, have invented a new, original, and ornamental Design for a Heater, of which the following is a specification, reference being had to the accompanying drawing, forming part hereof, wherein the figure is a front elevation of a heater exhibiting my new design.

I claim:

The ornamental design for a heater, as shown.

FRANK A. NIEBERDING.
